UNITED STATES PATENT OFFICE.

WILLIAM W. GEORGES, OF WASHINGTON, DISTRICT OF COLUMBIA.

METATARSAL-SUPPORT.

1,128,677.

Specification of Letters Patent. Patented Feb. 16, 1915.

Application filed November 5, 1914. Serial No. 870,424.

To all whom it may concern:

Be it known that I, WILLIAM W. GEORGES, a citizen of the United States, and a resident of the city of Washington, in the District of Columbia, have invented certain new and useful Improvements in Metatarsal-Supports, of which the following is a specification.

This invention relates to a support adapted to be placed upon the insole of a shoe and arranged so that it will support a weakened or deranged metatarsal. It is well known that the metatarsal bones frequently become weakened, or misplaced, so that one of them needs an extraneous support to hold it in its proper position whereby the pain resulting from the weakened or misplaced bone is partly, if not entirely, overcome.

The invention in its preferred embodiment consists of a layer of firm material, such for example as leather, to the under side of which is secured a plate having an arched portion which is adapted to hold the leather or other member up against the metatarsal at its weakened or misplaced part.

This plate having the arched portion may be, rigidly secured or it may be made adjustable in order that the plate may be moved so that it may be placed under any one of the three central metatarsals.

The invention is hereinafter more particularly described and will then be definitely claimed at the end hereof.

In the drawings accompanying and forming part hereof: Figure 1 is a top plan view of the bones of a foot placed upon my metatarsal support. Fig. 2 is a perspective view of my support viewed from the under side. Fig. 3 is a longitudinal section through the line 3—3 of Fig. 2. Fig. 4 is a transverse section through the line 4—4 of Fig. 2.

Referring now to the details of the drawings by numerals: 1 designates a sheet, preferably of leather, which I desire to make of the same shape as the heel and middle portion of the shoe in which the support is designed to be placed. Although this part

need not be any longer than shown in my drawings, I will hereinafter call it an insole. 50 To this insole 1 is secured a plate 2 of relatively small size, which is of elongated form and has an arched portion 5 designed to be located under any one of the inner metatarsal bones *a*, *b* or *c*, it being very seldom 55 the outer metatarsals are either weakened or misplaced. In the preferred embodiment of my invention, the plate 2 is riveted at one end to the insole by means of a rivet 6 and the plate is provided with a slot 7 through 60 which passes a screw 8 whereby the arched part 5 of the plate 2 may be adjusted, to the limits of the slot 7, so that the arched part 5 may be moved under whichever metatarsal needs the support. 65

From the foregoing and accompanying drawings, it will be seen that I have provided an extremely simple form of metatarsal support and one that takes up the least possible space in the sole of a shoe and 70 is yet capable of supporting a weakened or displaced metatarsal in just the proper position.

I am aware that many different forms of supports have been proposed, and a number 75 of them have been in use, directed more particularly to bracing the instep, or for other similar purposes, but I believe I am the first to produce the simple expedient shown in my drawing for bracing, in an effective and 80 simple manner, one of the metatarsals. It will be seen that the insole itself does not form the real support, but that it is a means for holding in place the relatively small and narrow plate, so that the arched portion of 85 the latter will be effectually held under the appropriate metatarsal and so that it cannot get misplaced.

What I claim as my invention is:

1. In a device of the character described, 90 an insole, and a plate provided with a protuberance designed to support a metatarsal, the plate being movably secured to the insole in such a manner that the protuberance may be moved to support a selected metatarsal. 95

2. In a device of the character described, an insole adapted to be placed in a shoe, and a plate of relatively small size secured to said insole and having an arched portion
5 adapted to be under one of the metatarsal bones, said plate being adjustably secured to said insole whereby it may be adjusted so that the arched part may be placed under

any one of the metatarsals, substantially as described. 10

In testimony whereof I affix my signature in presence of two witnesses.

WILLIAM W. GEORGES.
